UNITED STATES PATENT OFFICE

110,661

DESIGN FOR A DRESS

David William Price, New York, N. Y.

Application June 25, 1938, Serial No. 78,068

Term of patent 3½ years

To all whom it may concern:

Be it known that I, David William Price, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The characteristic feature of my design resides in the combination on the dress disclosed of the specific button trim on the skirt and sleeves as shown.

I claim:

The ornamental design for a dress, substantially as shown, and described.

DAVID WILLIAM PRICE.
